Primary Examiner—Doris Clark*Attorney, Agent, or Firm*—Laura G. Barrow**[57] CLAIM**

The ornamental design of a combined telephone booth and advertising display unit, as shown.

DESCRIPTION

FIG. 1 is a perspective view of a combined telephone booth and advertising display unit showing my new design.

FIG. 2 is a front elevation view thereof.

FIG. 3 is a right side elevation view thereof.

FIG. 4 is a bottom plan view thereof.

FIG. 5 is a top plan view thereof.

FIG. 6 is a left side elevation view thereof.

FIG. 7 is transverse cross-section of the combined telephone booth and advertising display unit taken along lines 7—7 of FIG. 1; and,

FIG. 8 is a rear view thereof.
